UNITED STATES PATENT OFFICE

FRIEDEMICH LUTZ, OF STUTTGART, GERMANY, ASSIGNOR TO UNION SPECIAL MASCHINEN-FABRIK, G. M. B. H., OF STUTTGART, GERMANY

ORNAMENTAL STITCH SEWING MACHINE

Application filed April 1, 1930, Serial No. 440,782, and in Germany May 4, 1930.

The invention relates to new and useful improvements in sewing machines, and more particularly to a sewing machine for forming lines of stitches so as to ornament a fabric surface or the edge of a fabric.

An object of the invention is to provide a sewing machine wherein the stitch forming elements are adapted to be shifted laterally of the line of feed for ornamenting the fabric by a single pattern drum operating through a common lever for shifting both the needle and complementary stitch forming mechanism, wherein the section of the drum controlling the stitch forming elements is interchangeable with other sections and wherein the timing of the drum relative to the stitch formation may be changed by interchangeable gears.

In the drawings:—

Fig. 1 is a view partly in section and partly in front elevation showing a sewing machine embodying the invention.

Fig. 2 is a view partly in section and partly in plan of the machine showing particularly the pattern drum and the parts operated thereby for shifting the position of the stitching elements.

Fig. 3 is a view partly in section and partly in side elevation showing the pattern drum and the devices which shift the needle and looper.

Fig. 4 is a development of one form of pattern cam used on said drum.

Figs. 5, 6, 7, 8, 9 and 10 are diagrammatic views showing different stitch ornamentalations which may be accomplished by the interchangeability of the pattern drum and the changing of the timing of the drum.

The invention is directed to a sewing machine and more particularly to a pattern mechanism for shifting the needle and looper laterally of the line of feed for ornamenting the surface of the fabric or the edge portion of the fabric.

The machine as illustrated includes a supporting bed 11 carrying an overhanging arm 12 on which is mounted a needle gate 13. A needle bar 14 reciprocates in this needle gate. The needle bar is reciprocated by a needle lever 15 pivoted at 16 to the overhanging arm

12 and connected through an eccentric strap 17 with an eccentric on the main shaft 18. Cooperating with the needle beneath the work support is a thread carrying looper 19 pivoted at 20 to a looper rocker 21. This rocker 55 is oscillated in the usual way to give a needle 55 avoiding movement to the looper and the looper is oscillated on the rocker so as to move the same into and out of the needle thread loop.

This is accomplished by a pair of links 22 and 23 which are pivotally connected at 24. The link 23 is pivoted at 25 to the needle lever extension 26. As the needle lever extension vibrates, through these links 22 and 23, it will 65 impart oscillations to the looper. The needle gate 13 is moved about a vertical axis by means of a link 27. This link 27 is pivoted to the upper end of a lever arm 34 attached to a sleeve 30 mounted for oscillations on a 70 fixed shaft 31 (see Fig. 3). The pivotal connection between the links 22 and 23 is mounted on a link 32 connected to the outer end of an arm 33 carried by the sleeve 30.

The sleeve 30 is oscillated or shifted by 75 means of a roller 28 which is adjustably carried by the lever arm 34. This roller 28 runs in a pattern cam 35. This pattern cam 35 is formed in the outer face of a drum 36. The drum is made in two sections. The section 36a 80 is provided with a cam groove and this section 36a is secured by bolts 37, 37 to the driven section of the drum 36b.

The driven section 36b carries a hub 38 which is mounted for free rotation on a supporting stud 39 mounted in the standard carrying the overhanging arm 12. The driven section 36b is provided with an internal gear 40. A pinion 41 meshes with this internal gear. Attached to and rotating with the 85 pinion 41 is a pinion 42 which meshes with a pinion 43 carried by the main shaft 18. This pinion 43 is readily detachable from the shaft and other pinions may be substituted therefor. Likewise the pinions 41 and 42 may be 90 removed and a pinion of different size substituted for the pinion 42. As the main shaft rotates it will rotate the pattern drum and the timing of the pattern drum relative to the 95 100

stitch formation may be changed by these interchangeable gears just referred to. By the changing of the timing of the drum is meant a change in the number of complete rotations of the main actuating shaft for each 5 rotation of the drum so that while the number of complete stitch cycles is changed, the timing of the lateral shifting of the needle and looper relative to the feed is not changed.

By the use of an internal gear the drum may 10 be made relatively large and still placed underneath the needle lever. This enables the pattern drum to be relatively large in diameter.

The pattern cam 35 may be of any desired 15 shape. The section 36a carrying this pattern cam may be readily removed and a new section substituted therefor having a differently shaped pattern cam. This is accomplished by removing the bolts 37 and this is all that is 20 necessary. As this pattern cam rotates, the roller 28 following the pattern cam will change the position of the lever arm 34 and this through the link 27 will change the position of the needle gate 13 and thus the needle 25 is shifted laterally of the line of feed.

The feed dog is indicated at 44 in the drawings; the needle at 45. The presser foot which holds the material on the work support is indicated at 46. This shifting of the lever arm 34 to set the needle gate at a fixed position also through the arm 33 will raise or lower the pivotal connection between the links 22 and 23 and thus either lengthen or shorten 30 the distance between the pivotal connection 35 25 of the link 23 to the needle lever extension and the connection of the link 22 to the looper and this will, of course, shift the oscillating position of the looper. The extent of oscillation imparted to the looper is precisely the same, but the field or position in which it oscillates is shifted to correspond to the shifting of the needle. Thus it is that through the 40 one common operating lever and a single roller running on a pattern drum, both the needle and looper are shifted laterally of the line of feed and the extent and timing of the shifting is determined by the pattern cam.

In Fig. 4 of the drawing the pattern cam is 50 shown in its full development and the roller 34 is at the position indicated at 1. This is the position of the first stitch formation in Fig. 5. As the pattern cam rotates, this roller 34 will take a position indicated by the broken 55 lines at 2; and during this time the roller has shifted laterally of the pattern drum so as to cause the needle and looper to shift and 60 make a stitch 2 in Fig. 5. The stitches which are formed during a single rotation of the drum are indicated by the positions 3, 4, 5, 6, 7, 8, 9 and 10.

The drum is so shaped as shown in Fig. 5 that the stitches 4, 5, 6, 7 and 8 are all in a line the same lateral distance from the initial 65 position of the needle. At 1 again the needle

is in line with its initial position. Thus it is that a line of stitches may be produced which when located at the edge of a fabric will give more or less of a scallop formation. The stitches from 4 to 8 may be over the edge and interlocked so as to form a chain of stitches 70 extending from the third stitch to the ninth stitch.

In Fig. 6 a stitch formation is illustrated which requires a changing of the pattern 75 drum and also a changing of the timing of the drum, as in this stitch formation there are eight stitches to each cycle and the pattern cam has been altered so as to produce this shifting back and forth of the looper.

In this form all of the stitches may be 80 enchain and placed over the edge of the fabric except stitches at the points indicated at 1, or all of the stitches may be placed in a fabric for ornamenting the surface of the 85 fabric. In the pattern shown in Fig. 7, the same timing of the drum is maintained but the pattern cam is again changed so as to produce different characteristics in the lateral shifting of the needle and looper.

In the form of ornamentation shown in 90 Fig. 8 the cycle has again been changed by the changing of the timing of the drum relative to the stitch formation so that six stitches are formed for each rotation of the drum. The pattern cam is also changed to give a 95 different type of lateral shift to the needle and looper.

In the ornamentation shown in Fig. 9 the 100 timing of the drum has again been changed so that during each cycle there are only two stitches. Inasmuch as the stitches are symmetrically disposed, that is, merely moved first laterally in one direction and then laterally in the other direction, this may all be 105 accomplished by the pattern cam without changing the timing of the drum.

In Fig. 10 the timing of the drum has been 110 changed so that five stitches are produced for each rotation of the drum and the pattern cam is shaped so that only every fifth stitch is placed laterally to one side of the other 115 stitches which are in line.

It will be understood that other forms of 120 ornamentation may be accomplished by the interchangeable pattern drums and the changing of the timing of the drum, and it will be noted that it is all accomplished through a very simple mechanism for shifting the needle and looper laterally which 125 includes only a single lever arm and a single roller running in the pattern cam. Only one pattern cam is necessary. This not only greatly simplifies the structure, but provides uniformity in the lateral shifting of the needle and looper.

Having fully described my invention, what I claim as new and desire to secure by Letters Patent is:—

1. The combination of a needle, means for 120

supporting said needle whereby the same may be shifted laterally, a looper cooperating with the needle, means for oscillating said looper and for permitting the oscillating position of said looper to be shifted, a feed dog, and mechanism for shifting the needle reciprocating position and the looper oscillating position laterally of the line of feed, including a sectional pattern drum, one of said sections being detachably connected to the other and having a pattern cam formed therein, means actuated by said pattern cam for controlling the stitch forming position of the needle and looper, the other section of said drum having an internal driving gear, an actuating shaft, and interchangeable gears between the actuating shaft and the internal gear of the drum.

2. The combination of a needle, means for supporting said needle whereby the same may be shifted laterally, a looper cooperating with the needle, means for oscillating said looper and for permitting the oscillating position of said looper to be shifted, a feed dog, and mechanism for shifting the needle reciprocating position and the looper oscillating position laterally of the line of feed, including a hub mounted for rotation, a drum section carried by the hub and having an internal gear and an interchangeable section bolted to said first-named section and having a pattern cam therein, means actuated by the pattern cam for controlling the stitch forming position of the needle and looper, an actuating shaft, and interchangeable gears operated thereby and engaging said internal gear on the drum for rotating the drum.

In testimony whereof, I affix my signature.
FRIEDRICH LUTZ.
